Atty's.

UNITED STATES PATENT OFFICE.

NOAH N. NEHER, OF WHITTIER, CALIFORNIA.

COMBINATION LOCK.

Original application filed April 12, 1923, Serial No. 631,572. Divided and this application filed March 18, 1925. Serial No. 16,381.

To all whom it may concern:

Be it known that I, NOAH N. NEHER, a citizen of the United States, residing at Whittier, in the county of Los Angeles and State of California, have invented new and useful Improvements in Combination Locks, of which the following is a specification.

This is a divisional application of the subject matter disclosed in my co-pending application, Serial No. 631,572, filed April 12, 1923. My co-pending application relates to improvements in combination locks for controlling the gasoline line upon vehicles, such as automobiles. The combination lock is adapted to be mounted upon the dashboard of the vehicle and actuates and controls a valve in the gasoline line leading to the motor of the vehicle.

The present application relates to the specific combination lock, and it is to be understood that although the combination lock has been previously disclosed as applied to a gasoline line lock, it is adapted for use in general application.

The primary object of this invention is to provide an improved form of combination lock adapted to control a slidable plunger which actuates the locking or latch element.

With the foregoing and other objects in view which will be made manifest in the following detailed description and pointed out in the appended claims, reference is had to the accompanying drawings for an illustrative embodiment of the invention, wherein:

Figure 1 is a front elevation of the improved lock;

Fig. 2 is a vertical section taken substantially on the line 2—2 of Fig. 1;

Fig. 3 is a perspective view showing the plunger and locking parts of the combination lock;

Fig. 4 is a view taken substantially on the line 4—4 of Fig. 2;

Fig. 5 is a perspective view showing the plunger and one of the sleeves about the plunger for controlling the sliding movement of the plunger; and

Fig. 6 is a vertical section taken substantially on the line 6—6 of Fig. 2.

Referring to the accompanying drawings wherein similar reference characters designate similar parts throughout, the dashboard of the vehicle is shown at D, and although the lock will be described as applied to the dashboard of the vehicle, it will be understood that any other suitable mounting may be employed in the general application of the lock. A plate, circular in form, which is indicated at 10, is mounted upon the front face of the dashboard D, and a bezel 11 is secured upon the plate as by rivets 12 having countersunk heads. The rivets extend through the dashboard D. A disc 13 is rotatable within the bezel 11 and is provided with a handle forming rim 14. The disc 13 is preferably countersunk, as indicated at 15, within the rim 14 to provide room facilitating the grasping of the knob 16 upon the plunger 17 extending through the disc. The plunger 17 extends through the dashboard D, and upon the under side thereof there is mounted a suitable frame 18 which carries a plate 19 through which the end of the plunger 17 extends. The end of the plunger 17 is squared or angular in form, as at 20, and extends through a corresponding aperture in the plate 19, so that the plunger is capable of sliding movement, but rotation of the plunger is prevented.

In use of the lock as upon a gasoline line lock for vehicles, a flexible element 21 is secured to the end of the plunger 17 and extends through a conduit 22 which may be secured to the frame 18. It will be readily understood that other operating or latching mechanisms may be actuated by the plunger 17, and that any suitable mechanism can be secured to the plunger so as to be operated thereby. Upon the under side of the dashboard D, there is mounted upon the plunger a pin 23 forming a projection on the plunger. A sleeve 24 is integral with the disc 13 and is disposed about the plunger 17. A second sleeve 25 is dis-

posed about the sleeve 24 so as to be rotatable thereon. This sleeve is provided with a flange 26 disposed upon the under side of the disc 13. A suitable screw 27, providing a projection upon the under side of the disc 13, is so arranged as to be adapted to engage a pin or projection 28 formed upon the flange 26 when the disc 13 is rotated. A leaf spring 29 is mounted upon the plate 10 and engages the flange 26 of the second sleeve 25, urging the second sleeve toward the under side of the disc 13. The leaf spring 29 provides a friction means, frictionally engaging the second sleeve 25, tending to resist rotation of the second sleeve when the disc 13 is rotated and when the projections 27 and 28 are disengaged. The ends of the sleeves 24 and 25, which are remote from the disc 13, are flush with each other and normally provide an abutment for the pin or projection 23 on the plunger, so that the plunger 17 cannot be caused to slide axially. A slot 24^a is formed in the sleeve 24, which is capable of receiving the lower portion of the pin 23. This slot is preferably angular, as at 24^b, providing a bayonet slot in the sleeve 24. The second sleeve 25 is provided with a slot 25^a capable of receiving the upper end of the pin 23. Upon the bezel 11 there is preferably formed a setting point P and upon the rim of the disc 13 there is preferably arranged numbered graduations C.

The operation of the lock is as follows: Considering the lock as being locked, that is, with the slots 24^a and 25^a in disalignment, so that the end surfaces of the sleeves provide an abutment for the pin 23, preventing sliding of the plunger 17, the disc 13 is first rotated, causing the screw 27 to engage the projection 28. The disc is continued to rotate until the proper graduation C is disposed opposite the setting point P. In such position the slot 25^a will be disposed opposite the pin or projection 23, but the slot 24^a will not be opposite the pin 23, but will be angularly spaced therefrom. After the sleeve 25 has been set in this manner, the disc 13 is rotated in the opposite direction until the proper graduation C is opposite the setting point P, in which case the slot 24^a will be in alignment with the slot 25^a, both of which slots will be opposite the pin 23. It will be understood that when the disc 13 is reversely rotated, the sleeve 25 will not tend to rotate with it, because of the spring 29. When the slots 24^a and 25^a are in alignment and opposite the pin 23, the knob 16 upon the plunger 17 can be pulled so as to slide the plunger 17 and actuate the locking mechanism or latch of the lock, which in the case of an automobile gasoline line lock opens the valve controlling the gasoline line. Such sliding movement

of the plunger 17 causes the pin 23 to enter the slots 24^a and 25^a. In this manner it will readily be appreciated that the lock will be opened. To again lock the lock, the plunger 17 is thrust forwardly so as to cause the pin 23 to slide out of the slots 24^a and 25^a, and by rotating the disc 13, the sliding movement of the plunger 17 is prevented.

In some cases it is desirable to hold the plunger 17 in the withdrawn or unlocked position. In these cases when the pin 23 is disposed within the slots 24^a and 25^a, the disc 13 can be rotated slightly, causing the pin 23 to enter the slot 24^b, which will prevent the plunger 17 from sliding back into its original or locked position. The pin 23 can be caused to pass out of the slot 24^b by swinging back the disc 13. It will be understood that the sleeves 24 and 25 constitute types of tumblers which are settable by the disc 13 to bring the slots in alignment to receive the projection upon the plunger.

It will be understood that various changes in the detail of construction may be made without departing from the spirit or scope of the invention as defined by the appended claims.

I claim:

1. A combination lock comprising a slideable, but not rotatable, plunger having a projection formed thereon, a disc rotatable about said plunger, and a sleeve disposed about said plunger and having a bayonet slot formed therein capable of receiving said projection so as to permit movement of the plunger and to lock the plunger in moved position, said sleeve being actuated by said disc.

2. A combination lock comprising a slideable, but not rotatable, plunger having a projection formed thereon, a disc rotatable about said plunger, a sleeve rotatable about said plunger, and a second sleeve rotatable about said sleeve, said sleeves being settable by said disc and having slots formed therein capable of receiving said projection so as to permit sliding of the plunger.

3. A combination lock comprising a slideable, but not rotatable, plunger having a projection formed thereon, a disc rotatable about said plunger, a sleeve rotatable about said plunger, and a second sleeve rotatable about said sleeve, said sleeves being settable by said disc and having slots formed therein capable of receiving said projection so as to permit sliding of the plunger, one of said slots in said sleeves being angular as and for the purpose described.

4. A combination lock comprising a slideable plunger having a projection formed thereon, a disc rotatable about said plunger and having a sleeve secured thereto also rotatable about said plunger, a second sleeve rotatable about the first sleeve and settable by said disc, there being slots formed in said

sleeves capable of receiving said projection so as to permit sliding of said plunger, and means frictionally engaging said second sleeve tending to resist rotation of said second sleeve.

5. A combination lock comprising a slideable plunger having a projection formed thereon, a disc rotatable about said plunger and having a sleeve secured thereto also rotatable about said plunger, and a second

sleeve rotatable about the first sleeve and settable by said disc, there being slots formed in said sleeves capable of receiving said projection so as to permit sliding of said plunger, the slot in the first sleeve being angular 15 as and for the purpose described.

In testimony whereof I have signed my name to this specification.

N. N. NEHER.
